FIG.14

FIG. 1 is a front, top and right side perspective view of a combined duplex electrical device and wall plate or similar article, showing one form of my new design wherein the duplex device consists of two switches;

FIG. 2 is a front elevational view of the form shown in FIG. 1;

FIG. 3 is a left side elevational view of the form shown in FIG. 1;

FIG. 4 is a right side elevational view of the form shown in FIG. 1;

FIG. 5 is a top plan view of the form shown in FIG. 1, the bottom being substantially a mirror image thereof;

FIG. 6 is a front, top and right side perspective view of a combined duplex electrical device and wall plate or similar article, showing a second form of my new design wherein the duplex device consists of a switch and a pilot light;

FIG. 7 is a front elevational view of the form shown in FIG. 6;

FIG. 8 is a left side elevational view of the form shown in FIG. 6;

FIG. 9 is a right side elevational view of the form shown in FIG. 6;

FIG. 10 is a top plan view of the form shown in FIG. 6, the bottom being substantially a mirror image thereof;

FIG. 11 is a front, top and right side perspective view of a combined duplex electrical device and wall plate or similar article, showing a third form of my new design wherein the duplex device consists of a switch and an outlet;

FIG. 12 is a front elevational view of the form shown in FIG. 11;

FIG. 13 is a left side elevational view of the form shown in FIG. 11;

FIG. 14 is a right side elevational view of the form shown in FIG. 11; and

FIG. 15 is a top plan view of the form shown in FIG. 11, the bottom being substantially a mirror image thereof.

The dominant features of my new design are shown in solid lines and reside in the combination with a wall plate of a duplex electrical device having two electrical members disposed on a generally flush body with a switch member having a raised boss therearound and a groove in the body connecting the switch member with the other electrical member, all shown.

This application is a continuation of all of applicant's co-pending applications Ser. Nos. D-83,006, D-83,015 and D-83,032 all filed on Dec. 14, 1964 and all abandoned subsequent to filing this application.

I claim:

The ornamental design for a combined duplex electrical device and wall plate or similar article, as shown and described.
